UNITED STATES PATENT OFFICE.

GEORGE H. F. HOLY, OF PITTSBURGH, PENNSYLVANIA, ASSIGNOR TO WESTINGHOUSE ELECTRIC AND MANUFACTURING COMPANY, A CORPORATION OF PENNSYLVANIA.

GEAR-CASE.

1,248,493.

Specification of Letters Patent.

Patented Dec. 4, 1917.

Application filed December 18, 1914. Serial No. 877,899.

To all whom it may concern:

Be it known that I, GEORGE H. F. HOLY, a citizen of the United States, and a resident of Pittsburgh, in the county of Allegheny and State of Pennsylvania, have invented a new and useful Improvement in Gear-Cases, of which the following is a specification.

My invention relates to gear-inclosing members, and it has special reference to gear cases that are adapted to protect such meshing gears and pinions as are employed in connection with the propelling motors of electric locomotives and the like.

One of the objects of my invention is to provide a device of the above-indicated character which shall be simple and compact in construction and readily assembled and taken apart while in position beneath the cab floor of the locomotive without requiring the removal of adjacent apparatus.

Another object of my invention is to provide an improved construction for preventing the leakage of lubricating material from the gear case, while also permitting the removal of the outer and under sides of the case without disturbing the rear or motor side.

A further object of my invention is to provide a gear case having means for readily permitting an external temporary support of the pinion shaft, whereby the motor bearings may be removed for inspection or repairs without necessitating the removal of the gear case.

In the prior art, when it was desired to remove a gear case of the usual longitudinally-split type, it was often necessary to first remove the adjacent apparatus, particularly when taking off the upper half of the case, because of the necessity of moving it vertically a considerable distance. Again the use of a track pit has been required to remove the lower half of the case, by reason of the usual relatively small clearance between the gear case and the ground. Moreover, when the bottom wall of the case has been closed by means of the customary riveting, an undesirable leakage of oil has occurred after a certain length of service. Furthermore, the removal of the motor bearings has required the previous removal of the entire gear case before the pinion shaft could be suitably externally supported, to permit of the desired bearing inspection.

According to my present invention, I provide a gear case embodying means for obviating the above-mentioned disadvantages. In one form, wherein a gear and a plurality of pinions meshing at widely separated points are employed, my gear case preferably embodies an upper half comprising a pair of complementary members for respectively incasing one pinion and a part of the gear and adapted to be detachably secured together in a plane at substantially right angles to an aligned side of each, which, if joined, would pass substantially opposite the center of the gear, and a lower half that is adapted for removable attachment to the said aligned sides. The case is thus provided with a plurality of peripheral splits, the one in the upper half being disposed substantially perpendicular to the split between the upper and lower half, and the various parts being detachably secured together in pairs. The lower half of the gear case preferably comprises two portions: The lowermost part of the outside wall is provided with an upwardly-bent peripheral extension of substantially L-shape in section, and the inner, or motor, side wall extends substantially parallel to the outer wall and is adapted to form a continuation of, and a substantially oil tight joint with, the said extension. The excess lubricating material may be securely held in the trough thus provided. In order to permit an externally located support of the pinion shaft for purposes of bearing inspection, I provided a normally suitably covered opening in each part of the upper half of the gear case that respectively approximately register with the corresponding pinion. The motor shaft may thus be readily supported to permit bearing inspection without disturbing the gear case as a whole.

In the accompanying drawing, Figure 1 is a view in longitudinal section taken on the line I—I of Fig. 2 and illustrating a gear case constructed in accordance with my invention; Fig. 2 is a view, in front elevation, with a portion broken away, of the gear case shown in Fig. 1; and Fig. 3 is a view, in elevation, of a component member of the gear-case.

Referring to the drawing, the apparatus here shown comprises a gear-wheel 1 which is suitably secured to a jack shaft or wheel axle 2, as the case may be; a plurality of

pinions 3 and 3^a that are adapted to mesh with the gear 1 at widely separated points and are respectively mounted upon shafts 4 that rotate within suitable, preferably split, bearing-housings 5, and are secured to the threaded ends of the respective shafts 4 by means of suitable nuts 6; and a gear case comprising a plurality of complementary members 7 and 8 which together are adapted 10 to form an upper half of the case and respectively inclose the pinions 3 and 3^a and a corresponding portion of the gear wheel 1, and a member 9 that is adapted to complete the inclosure of the gear wheel, substantially 15 constituting the lower half of the gear case. The complementary members 7 and 8 are secured together by means of a plurality of suitable bolts 10, while the member 9 is suitably detachably secured to the members 7 20 and 8 by a plurality of bolts 11 and 12, as hereinafter more fully set forth.

The members 7 and 8 respectively comprise a preferably integrally formed outer wall 13 and top wall 13^a which may be 25 suitably secured to a flange of the bearing housing 5 by means of a plurality of bolts 15. A member 14, best shown in Fig. 3, is adapted to form, with the adjacent portion 30 of the housing 5, the rear or inner wall of the member 7, and is provided with a semi-circular opening 14^a for receiving the corresponding pinion shaft 4, and with a suitable lug 14^b for attachment to the motor frame (not shown). The member 8 has a 35 rear wall member that is similar, but reversely disposed or complementary, to the member 14, as will be understood. The member 14 may be secured to the abutting portions of the top walls 13^a by a plurality 40 of bolts 14^b that severally extend through a plurality of lugs 14^c of the walls 13^a. The arrangement of parts is thus such that the housing 5 is adapted to constitute a portion of the rear or inner wall of the gear-case members 7 and 8.

The abutting sides of the walls 13^a and of the complementary rear walls 14 are respectively provided with lugs or flanges 16 and 16^a through the abutting pairs of which the 50 bolts 10 extend. Each of the members 7 and 8 is preferably provided with a suitably-covered hand hole 17 in the upper wall 13^a for permitting lubrication of the meshing gear wheel and pinions and an 55 outer wall opening that substantially registers with the corresponding pinion and is covered by means of a suitably dished cover-member 18 that may be secured to the corresponding gear-case wall 13 by means of a 60 plurality of bolts 19.

The lower half 9 of the gear case may be provided with a suitable centrally-located opening 20, the upper half of which is collectively formed by the members 7 and 8 65 and has the lowermost portion of its outer

wall 21 provided with an inwardly and upwardly-bent peripheral extension 22 of substantially L-shape in section having a straight upper edge 23 that extends substantially parallel to the split between the 70 upper and lower parts of the gear case. The inner wall 24 of the member 9 extends substantially parallel to the outer wall 21 thereof and has its lower end provided with a shoulder 25 for suitably engaging the 75 straight edge 23 of the peripheral extension 22 to form a suitable oil-tight joint therewith. The inner wall 24 constitutes a continuation of the extension 22, the two portions of the lower half 9 collectively comprising an incasing member having the customary section of substantially U-shape. The wall 24 may be suitably secured to the 80 motor frame (not shown) by means of a bracket member 24^a. A trough 26 is thus 85 provided at the lowermost portion of the gear case to effectively prevent any leakage of excess lubricating material, while, at the same time, the outer portion of the lower half 9 may be readily removed without disturbing the position of the inner side 24 and without requiring much downward movement in order to clear the end of the gear wheel 1. The member 9 is provided, 90 on both sides of the extension 22, with an 95 outwardly-bent extension of substantially L-shape in section that may be secured to the motor housing by a plurality of bolts 15^a.

The lower half 9 of the gear case is provided; on one radially-disposed edge, with 100 suitable lugs 27 and 27^a that respectively abut against corresponding front and rear wall lugs 27^b and 27^c of the member 7, and the bolts 11 extend through the abutting lugs. A similar construction, involving lugs 28 and 28^a and suitable rear lugs (not shown) and the bolts 12, obtains for 105 securing the member 9 to the member 8.

It will be noted that the split or line of contact 29 between the complementary members 7 and 8 that constitute the upper half 110 of the gear case is shown as substantially perpendicular to the aligned splits or lines of contact 30 and 30^a between the members 7 and 9 and 8 and 9, respectively, and that 115 the planes of contact 30 and 30^a, joined, would pass substantially through the center of the gear wheel 1.

The removal of parts of my gear case, 120 particularly the outer walls, which will usually suffice, may be accomplished conveniently, rapidly and without requiring the removal of adjacent apparatus. To take off the member 7 alone, for example, certain of the bolts 10, 11, 14^b, and 15 are removed, 125 whereupon the member may be readily slid off either to the left or perpendicularly to the plane of the gear, as desired. A similar procedure obtains for removing member 8, and the ease of removal of the lower mem- 130

ber 9 has already been pointed out. Moreover, by leaving the bolts 10 tightened, the members 7 and 8 may be readily removed, as one piece, perpendicularly to the plane 5 of the gear.

Although I have shown my gear case as comprising six separate members fastened together in a certain manner, it will be understood that the structure need not involve 10 all the details illustrated. For example, for convenience in manufacture and installation, the outer walls 13 of the members 7 and 8 are made separate and are bolted together, whereas, in some cases, it may be 15 desirable to have these members in one piece or to merely provide them with overlapping edges and dispense with the bolts.

To permit removal of the motor bearing housing 5 for the purpose of inspection or 20 repairs, it is merely necessary to remove the bolts 15 and to loosen the bolts 19 to allow removal of the cover member 18 over the corresponding pinion 3 or 3^a, and then dispose a suitable lifting jack or other sup- 25 porting member beneath the corresponding nut 6, whereupon the split housing 3 may be readily removed without necessitating the removal of the gear case as a whole.

I do not wish to be restricted to the specific structural details or arrangement of 30 parts herein set forth, as various modifications may be made within the spirit and scope of my invention and I desire, therefore, that only such limitations shall be imposed as are indicated in the appended 35 claims.

I claim as my invention:

1. The combination with a gear wheel and a plurality of pinions meshing therewith 40 at materially separated points, of an incasing device having complementary parts respectively adapted to inclose one of said pinions and a portion of the gear wheel and to be secured together and another part 45 adapted to complete the inclosure of the gear wheel and to be secured to each of said first parts.

2. A gear-incasing device comprising a side-wall having an inwardly bent peripheral extension of substantially L-shape in 50 section and a straight wall portion co-operating therewith to collectively constitute a member of substantially U-shape in section.

3. A gear-incasing device comprising a side-wall having an inwardly bent peripheral extension of substantially L-shape in 55 section, the free end of said extension being disposed substantially parallel to said side wall, and a second side wall forming a continuation of said free end and adapted to make a substantially oil-tight joint therewith.

4. A lower half of a gear case comprising 60 a side wall provided, at its lowest point, with

an inwardly bent peripheral extension of substantially L-shape in section that has a substantially straight upper edge and a second side wall extending substantially parallel to said first wall and having a lower 70 edge that is adapted to make a readily separable, substantially oil-tight joint with the upper edge of said extension.

5. The combination with a supporting frame, a driving and a driven shaft mounted 75 therein, and a meshing pinion and gear wheel disposed on said shafts, of a lower half of a gear case comprising an outer side wall provided, at its lowest point, with an inwardly bent peripheral extension of substantially 80 L-shape in section that has an upper edge substantially parallel to the upper edge of said lower half, said side wall being elsewhere provided with an outwardly bent peripheral extension of substantially 85 L-shape in section that is secured to said frame, and an inner side wall extending substantially parallel to said outer wall and having a lower edge provided with a shoulder for forming, with the upper edge of said 90 first extension, a substantially oil-tight contact joint, whereby leakage of lubricating material from the gear case is substantially prevented and the outer portion of the said lower half of the case may be readily removed. 95

6. The combination with a meshing gear wheel and pinion disposed in the same plane, of an incasing device comprising a plurality of separate parts secured together, one of 100 said parts being adapted to inclose the pinion and a portion of the gear wheel, said part having a relatively large side-wall opening approximately registering with the pinion. 105

7. The combination with a gear wheel and a plurality of materially separated pinions meshing therewith, of an incasing member having complementary parts respectively adapted to inclose one of said pinions and 110 a portion of the gear wheel, said parts each having a relatively large side wall opening approximately registering with the corresponding pinion, and detachable cover members for said openings. 115

8. A gear-incasing device comprising a side-wall having an inwardly bent peripheral extension of substantially L-shape in section adapted to constitute an oil pan, and a straight wall section co-operating with said 120 oil pan to collectively constitute a member of substantially U-shape in section.

9. A gear-incasing device comprising a side-wall having an inwardly bent peripheral extension of substantially L-shape in 125 section, the free end of said extension being disposed substantially parallel to said side wall and constituting a pocket for lubricating material, and a second side-wall forming a continuation of said free end and 130

adapted to make a substantially oil-tight joint therewith.

10. The combination with a meshing gear wheel and pinion, of an incasing member closely fitting the periphery of said gear wheel and having an independently removable wall section for inclosing a portion of said gear and another independently removable section for inclosing the pinion and another portion of said gear, said first wall

portion having an integral oil pan into which said gear wheel is adapted to dip.

In testimony whereof, I have hereunto subscribed my name this 15th day of Dec. 1914.

GEORGE H. F. HOLY.
